UNITED STATES PATENT OFFICE.

VICTOR H. HARBERT, OF CHICAGO, ILLINOIS, ASSIGNOR TO E. PAYSON SMITH, OF CHICAGO, ILLINOIS.

BRAKE-GEAR MOUNTING.

Application filed April 11, 1927. Serial No. 182,742.

My invention relates to mountings for the gear mechanism, employed in operating the hand brakes of railway cars, whereby the gear mechanism is suitably supported from 5 the end sill members of the car or its under-frame; the invention at the same time involving a construction which will enable the gear mechanism to be readily removed and replaced, should occasion require without 10 the necessity of removing the entire mounting or housing from the end sill member of the car.

The objects and advantages of my invention will be readily comprehended from the 15 detailed description of the accompanying drawings wherein—

Figure 1 is an elevation of my improved mounting with the gear mechanism therein and showing portions of the brake-staff and 20 end sill of the car.

Figure 2 is a plan view with portions of the floor support and reinforcing bar of the car frame broken away; while the brake-staff is shown in section.

Figure 3 is a side sectional elevation.

Figure 4 is an elevation of the inner end or side of the mounting with portions shown in vertical section.

Figure 5 is a perspective view of the top 30 element or member of the housing.

Figure 6 is a perspective view of a bracket member employed on the inner side of the end sill.

My invention comprises a mounting more 35 especially intended to be secured to the end sill of a car, the sill being in the nature of a channel beam 10, see Figure 3, wherein the top and bottom flanges of the beam are disposed outwardly, relative to the car end, 40 while the vertical web portion on the inner side is provided with an angle bar 11, which is frequently employed for supporting a portion of the car floor while at the same time acting as a stiffener for the end sill. The 45 angle bar is usually riveted to the web of the end sill with one leg disposed horizontally inward as disclosed in Figures 2 and 3.

The mounting consists of the top plate or member 12 and the bottom plate or member 50 13 which are formed to suitably support the gear mechanism therebetween.

The top member 12 is substantially of rectangular formation, as shown in Figure 5, having the flat portion 14 offset slightly

above the plane of the flat portion 15 and 55 connected by the upwardly sloping wall 16; the plate being preferably reenforced by the sloping ribs 17 extending transversely of the flat portion 15 and the intermediate portion 16 and terminating adjacent to the inner longitudinal edge of the flat portion 14. The top plate is further reenforced by providing the depending side portions or flanges 18 which preferably extend about the four sides of the plate; with the flanges 18 at opposite sides increasing in depth toward the forward 60 outer end of the plate to provide the depending lobe portions 19.

The bottom member 13 consists of a substantially rectangular flat portion 20 corresponding in length and width with the flat portion 15 of the top plate 12. The opposite ends of the portion 20 terminate in upwardly disposed end walls or lobes 21 adapted to have partial lapping relation with the 70 lobes or ears 19 of the top plate. In the particular exemplification, the end walls 21, 21 are shown lapping the inside of the lobes or extensions 19 of the top plate, to which they are suitably secured, preferably 75 by means of rivets 22 see Figures 3 and 4. The bottom plate 13 intermediate of its ends is provided with an inwardly extending arm 23 which is shown offset downwardly, in order to position the driven mechanism in 80 the desired horizontal plane, and made tapering toward its ends. The free end of the arm 23 is therefore disposed in a plane beneath that of the flat portion 20 of the bottom member and provided with a flat upper 85 surface as shown at 24 in Figure 3. In order to provide sufficient strength the arm 23 is also shown provided with the longitudinally disposed reinforcing ribs 25, thus providing the bottom plate with proper 90 strength to support the gear mechanism.

The top and bottom members at their forward outer ends are both apertured to receive the brake-staff 26 to which a drive pinion of any suitable construction, as shown 100 for example at 27, is secured intermediate of the surface 15 of the top plate and the surface 20 of the bottom plate. The aperture in the bottom plate is somewhat smaller in diameter than the diameter of the main portion of the brake-staff to merely receive the reduced lower end of the brake-staff. The bottom plate about the brake-staff receiving 105

aperture is preferably provided with an encircling boss as at 28 on which the main portion of the brake-staff rests.

The inner end of the arm 23 of the bottom plate supports the driven gear 29 and the spool or drum 30, the latter being intended to receive the usual chain connected with the brake mechanism. The bottom plate with its arm 23 is of length somewhat greater than the length of the top plate and therefore extends inward of the end sill 10 of the car with the result that the journal of the driven elements of the gear mechanism is located in a vertical plane rearward of the vertical plane of the end sill as shown in Figure 3; while the top plate 12 is intended to be secured at its inner end 14 to the lower flange of the end sill, by means of rivets as shown at 31, or otherwise, and is not intended to extend beyond the inner vertical face of the end sill.

In order to suitably support the driven elements, or rather to support the journal or pin 32 of said elements, I provide a flat, preferably rectangular plate 33, apertured to receive the pin 32 while preventing the head 34 of the pin or bolt from passing therethrough, as shown in Figure 4. The bolt 32 is shown preferably provided with a ferrule 35 or spacing collar 35 resting at its upper end in the countersunk portion about the bolt-receiving aperture in plate 33, while its lower end rests in a similar countersunk portion about the bolt-receiving opening in the end of arm 23 of the bottom plate.

It is apparent that with the plate 33 in place and the nut 36 secured to the bolt 32, the driven elements will be maintained in place during shipment of the mounting and the gear mechanism, namely while the mounting is still unattached to a car.

In the exemplification as more clearly shown in Figure 4, the driven gear 29 on its lower side is shown provided with an elongated hub 37 having a reduced end which fits into the spool 30; said reduced end and the opening in the spool being of non-circular formation in order to induce rotation of the spool with the driven gear 29. The opening through the hub 37 of the driven gear and the opening through the spool 30 are shown longitudinally grooved to provide the oil channels 38.

In order to properly support the inner end of the gear mechanism and to reinforce the mounting against the inward pulls or strains encountered during brake operation, I provide a bracket element 39. This bracket element is preferably of the rectangular box-like formation shown, with its bottom 40 of slightly greater width than the top wall 41; while the end walls 42 are therefore also slightly wider at the lower ends, thus providing the off-set shown at 43 in order that the upper end of the bracket element 39 may

fit against the vertical leg or portion of the angle bar 11 while the lower end thereof may extend beneath the angle bar and abut against the vertical face of the end sill 10, as shown in Figure 3. The bracket element 39, for the purpose of giving it sufficient strength, is shown preferably provided with the transverse webs 44 disposed between the top face 41 and the bottom face 40. The side of the bracket element 39 which is to be disposed against the angle bar 11 and end sill 10 is provided with a side wall 45 having the shoulder 43 like the end walls 42; and this side wall 45 is provided with suitable apertures to receive the attaching means or rivets 46 whereby the bracket element 39 is riveted to the vertical portion of the angle bar 11 and the vertical web of the end sill 10, see Figures 3 and 4; while the top wall 41 of the bracket element is shown provided with an aperture at 47 which enables the bracket member to be riveted or otherwise secured to the horizontal portion of the angle bar 11 as by means of the rivet 48, see Figures 3 and 4.

In applying the mounting to the car, the plate 33, which holds the journal pin or bolt 32 of the driven mechanism in place, is riveted to the bottom face 40 of the bracket element 39; the bottom face 40 of the bracket element being provided with rivet or bolt-receiving openings as shown at 49 adapted to receive the rivets 50, shown in Figure 4. The bottom wall 40 of the bracket element is also shown provided with the non-circular or rectangular opening 51 to receive the head 34 of the journal pin or bolt 32 and prevent rotation of the pin. It is evident from this construction that even if the nut 36 of the bolt should accidentally become removed the journal pin or bolt 32 will be held in place by the plate 33.

With my improved construction it is apparent that the gear mechanism may be readily removed without dismantling the mounting beyond disconnecting plate 33 from the bracket element 39 which merely involves the removal of the rivets 50. At the same time the rigid bracket element 39, in conjunction with the bearing plate 33, will firmly hold the mounting against the inward pulls and strains encountered during brake-applying operation.

The construction as disclosed in the drawings is believed to be the best embodiment of the invention, but modifications may be made in certain details without, however, departing from the spirit of the invention.

What I claim is:

1. In a brake gear mounting, a top plate having a flat top along the inner end thereof adapted to be secured to the bottom flange of a car end sill, depending flanges at the sides of the outer end of the plate beyond the flange of the car end sill, a bottom plate

secured at its outer ends to a portion of the depending flanges of the top plate, the bottom plate being provided with an extension disposed inwardly from one longitudinal side and adapted to support the driven elements of the gear mechanism, and a separate box-like bracket member adapted to be secured to the inner side of the car end-sill beyond the inner end of the top plate, with the bottom of the bracket disposed above the axis of the driven gear.

2. A brake gear mounting comprising a top plate, a bottom plate, gear mechanism mounted between the plates, and a separate box-like bracket member arranged beyond the inner end of the top plate with one side thereof provided with a vertical wall adapted to extend parallel with the vertical web of a car end sill and to be secured thereto while the bottom wall of the bracket has bearing relation with the axis of the driven gear.

3. A brake gear mounting comprising a top plate adapted to be secured to the lower flange of a car end sill, a bottom plate secured at one end to the top plate, gear mechanism mounted between the plates, a journal-pin holding plate disposed above the driven gear, and a bracket member disposed above said holding plate with one vertical side secured to the inner side of the car end sill rearward of the inner end of the top plate.

4. A brake gear mounting comprising a top plate adapted to be secured to the lower flange of a car end sill, a bottom plate secured at one end to the top plate, gear mechanism mounted between the plates, a pin

holding plate arranged above the driven gear, and a box-like bracket member secured at the bottom to said last plate while one side is secured to the vertical web of the end sill on the inner side thereof.

5. A brake gear mounting comprising a top plate provided with flat portions along the inner and the outer longitudinal sides of the plate arranged in different horizontal planes, said flat portions being united by an intermediate sloping portion, a bottom plate secured at the opposite sides to the top plate, driving gearing mounted between the plates, driven gearing mounted on the inner end of the bottom plate, a journal-pin holding plate disposed above the driven gearing, a rectangular box-like bracket member secured on said last plate while the side wall of said member is secured to the vertical web of the end sill rearward of the top plate.

6. A brake gear mounting, comprising a top plate having a flat portion adapted to be secured to the lower flange of a car end sill, a bottom plate secured at its outer end to the outer end of the top plate, gear mechanism mounted between the plates, a holding plate for the journal pin of the driven portion of the gear mechanism and disposed above said mechanism, and a bracket member secured to said holding plate with one vertical side secured to the inner side of the car end sill rearward of the inner end of the top plate, said bracket member being socketed to receive the head of the journal pin to prevent rotation thereof.

VICTOR H. HARBERT.
